UNITED STATES PATENT OFFICE.

MILTON A. HAMILTON, OF DETROIT, MICHIGAN.

BARREL-COMPRESSING MACHINE.

SPECIFICATION forming part of Letters Patent No. 439,278, dated October 28, 1890.

Application filed May 25, 1889. Serial No. 312,050. (No model.)

To all whom it may concern:

Be it known that I, MILTON A. HAMILTON, a citizen of the United States, residing at Detroit, county of Wayne, State of Michigan, have invented a certain new and useful Improvement in Barrel-Compressing Machines; and I declare the following to be a full, clear, and exact description of the invention, such as will enable others skilled in the art to which it appertains to make and use the same, reference being had to the accompanying drawings, which form a part of this specification.

My invention has for its object a novel compressing-machine more especially designed for use in the manufacture of barrels and kegs made from woven fabric and for compressing said fabric upon the heads for hooping or otherwise securing the compressed fabric with the heads, all as more fully herein-after specified, pointed out in the claims, and illustrated in the accompanying drawings, in which—

Figure 1 is a plan view of the device embodying my invention, showing the rim of the friction-pulley broken away. Fig. 2 is a side elevation of the same. Fig. 3 illustrates modifications of my invention. Fig. 4 is a sectional view on the line $\alpha\alpha$, Fig. 1.

In the construction of certain devices from woven fabric and otherwise a very satisfactory and efficient method of securing the head in place in the body of the package, as in a barrel or keg, is to compress the extremities of the said body upon the periphery of the said head, in which compressed position the body is held firmly upon the head by a hoop or other means. My invention is intended to secure this compression, and is carried out as follows:

40 A represents any suitable support.

B is a driving-shaft properly journaled on said support and provided, preferably, with a friction hub or head B'.

B² is the driving-pulley.

45 C is a rotatable shaft suitably journaled on the support and provided with right and left hand screw-threads, as indicated at $c c'$, and also with sliding or traveling nuts $c' c^2$, constructed or provided with a fastening device 50 to engage the ends, respectively, of a rope D, as shown at $c^2 c^3$.

E is a friction-pulley on the screw-threaded shaft C, preferably constructed with a broadened rim E' and a central hub E² and friction-rim E³.

55 The friction-head B' is so arranged as to be moved laterally to form contact either with the rim E' or with the rim E³, as may be desired. To accomplish this purpose, an operating-lever F is suitably engaged therewith, whereby said head may be moved readily at the will of the operator. In its normal position said head may rotate between said rim E' and the rim E³, out of contact with either. To restore the said head to this normal position after being thrown in either direction by the operator, any suitable device may be employed—as, for instance, the lever may be weighted, as shown at F', to accomplish this result.

70 G denotes a barrel or keg, about which the rope D is shown engaged in a proper manner to secure the desired compression. The rope is looped about the barrel or keg, the ends being lapped past each other and leading to 75 the respective traveling nuts C' C². The shaft C being provided with right and left hand screw-threads toward its extremities, it is obvious that when said shaft is rotated in the proper direction the two nuts to which the 80 two ends of the rope are attached will move away from each other, pulling the looped rope therewith, thereby compressing the end of the body of the barrel upon the head very firmly. The hoop G' is then applied to hold the 85 compression secured, when the rope may be relaxed by rotating the shaft C in the opposite direction, and thereby causing the nuts to travel toward each other, slackening up the rope. It will be seen that greater power is 90 desired to secure the compression than to slacken the rope; also, that the latter operation may be accomplished more quickly than the former. To secure these respective results, the friction-head B' is forced against 95 the rim E' to pull the rope tight upon the barrel, the circumference of the rim adding to the power secured, while the frictional contact secured provides for the slipping of the head B' thereupon when too great tension is 100 secured, preventing liability of breakage. By throwing the friction-head upon the rim E³,

the same being of small diameter, the shaft C is reversed swiftly to slacken the rope and run the nuts into proper position for a new operation. The head B' being restored to its 5 normal position, the driving-shaft may continue to rotate continuously in the same direction. As the said head is first moved in one direction against the rim E' and in another direction against the rim E³, it is clear o that the shaft C will be rotated thereby in opposite directions.

The device is very simple and inexpensive and of great efficiency.

The construction of the friction-pulley E 15 with rims E' and E³ makes it a double friction-pulley. The special benefits of a friction device to control the operation of the shaft C might be secured by other arrangements and constructions of the friction mechanism with- 20 in the scope of my invention.

While I have described the shaft C as constructed with right and left hand screw-threads, such a construction is not indispensable within the scope of my invention, as it 25 might be threaded in a single direction and the rope passed about a pulley H, as shown in Fig. 3. So, also, it is not essential to my invention that the shaft C be provided with two traveling nuts, as one end of the cord 30 might be secured to a permanent or fixed fastening. I desire to so construct the pitch of the threads upon said shaft that the degree of pitch will hold the compression of the fabric in required subjection when the lever is 35 released without the employment of any additional device for this purpose. Both ends of the rope might be engaged with a single nut, as indicated in Fig. 3, one end being led

about the pulley H, said pulley serving to reverse the direction of the movement of the 40 extremity of said rope. In full lines the rope is shown in Fig. 3 as engaged with the two nuts C' C³, both traveling in the same direction, the pulley reversing the direction of the rope at one extremity. The dotted lines show 45 the extremity of the rope passed about the pulley carried to the nut C³, both extremities of the rope being thus engaged therewith.

What I claim as my invention is—

1. In a barrel-compressing machine, the 50 combination, with a rotatable screw-threaded shaft, of one or more nuts traveling in the same direction upon said shaft, a rope having its extremities engaged with said nut or nuts, and a pulley upon which the bight of said rope 55 is engaged to reverse the direction of one end of said rope, substantially as set forth.

2. The combination, with a support, of a screw-threaded shaft journaled thereupon, a friction-pulley located upon said shaft and provided with rims E' and E³, one of greater circumference than the other, whereby the said shaft may be rotated in one direction faster than in the other, a driving-shaft provided with a friction-head to engage said rims at 65 the will of the operator, one or more traveling nuts located upon the screw-threaded shaft, and a rope connected to said nut or nuts, substantially as set forth.

In testimony whereof I sign this specification in the presence of two witnesses.

MILTON A. HAMILTON.
